DESIGN FOR AN AIRPLANE

Walter F. McGinty, Alameda, Calif., assignor to
Batwing Aircraft Company, a copartnership,
Alameda, Calif.

Application June 29, 1936, Serial No. 63,573

Term of patent 7 years

To all whom it may concern:

Be it known that I, Walter F. McGinty, a citizen of the United States, residing at Alameda, county of Alameda, State of California, have invented a new, original, and ornamental Design for an Airplane, of which the following is a specification, reference being had to the accompanying drawing, forming part thereof.

Fig. 1 is a plan view of an airplane embodying my design;

Fig. 2 is a front elevation of the airplane illustrated in Fig. 1;

Fig. 3 is a rear elevation of the same; and
Fig. 4 is a side elevation of the same.

I claim:

The ornamental design for an airplane, substantially as shown.

WALTER F. McGINTY.
